(57) **CLAIM**

The ornamental design for a toilet brush dredge set, as shown and described.

DESCRIPTION

FIG. 1 is a front, right and top perspective view of a toilet brush dredge set, showing my new design.

FIG. 2 is a front, left and bottom perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof; and,

FIG. 9 is a front, right and top perspective view of the toilet brush dredge set in use with the lid open.

The broken lines show portions of the toilet brush dredge set that form no part of the claimed design.
